UNITED STATES PATENT OFFICE.

ERASTUS C. NELSON, OF EVANSTON, ILLINOIS.

FIRE-EXTINGUISHER HOLDER.

SPECIFICATION forming part of Letters Patent No. 322,468, dated July 21, 1885.

Application filed May 16, 1885. (No model.)

To all whom it may concern:

Be it known that I, ERASTUS C. NELSON, a citizen of the United States, residing at Evans-
5 ton, Illinois, have invented certain new and useful Improvements in Fire-Extinguishing-
Fluid Holders, of which the following is a specification.

The object of my invention is to facilitate the removal of the top of the holders or retainers for fire-extinguishing fluids; and the invention consists in the details of construction hereinafter described.

In the drawings, Figure 1 represents a front elevation of the top of a holder. Fig. 2 is a portion of a holder with a part broken away to show a section of the top; and Fig. 3 is a perspective view of the under side of the top of the holder.

In the drawings, A represents the holder; 20 B, the top; C, a piece attached to the under side of the holder; D, a point or edge of such piece turned up against the top; E, the staple to which the ring for suspending the holder is attached; and F, such ring.

25 In making a holder or retainer for fire-extinguishing fluids containing my improvement, I take a holder of the ordinary kind, consisting of a tube about twenty inches in length and two inches in diameter. This tube is closed by a top of soft or thin tin or other suitable metal, which is usually soldered onto the upper end of the holder in such a way that the same can be easily removed by tearing or cutting the tin. To facilitate this cutting or 30 tearing I attach to the under side of the top an additional piece of hard metal, preferably sheet-steel, so that it will form a sharp and hard cutting point or edge. This piece is bent out from the top proper a short distance, and 35 the point or edge is turned up against the same, as shown in the drawings. As represented in the drawings, this portion of the supplemental piece attached to the top is shaped to a sharp point sloping away at the 40 sides, so that it will readily and easily penetrate the tin composing the top and cut through the same, by which the tearing is begun and

facilitated. It need not, however, be brought to a point if it be made so as to present a sharp edge to the tin, that can be jerked or pulled through the same. To thus pull the point or edge of the supplemental piece of the top up and through the top, so as to cut the same, I pass a staple down through the top and through the supplemental piece, where it is fastened by turning the end of the staple to one side. A ring is passed through the upper end of the staple, by which the holder can, when not required for use, be suspended to a nail or hook in the wall. When the holder 50 is needed for use, this ring presents a hole for the hand, so that the staple can be jerked or pulled up, causing it to pull or jerk the point or edge of the supplemental piece of the top through the same and effect the commencement of the tearing or cutting above mentioned. The top, being cut or torn through at this place, can easily be jerked off by a continued pull on the ring. In this way there will be no difficulty in effecting a quick and complete removal of the top when it is desired to 55 apply the fluid contained in the holder to extinguish a fire.

What I claim as new, and desire to secure by Letters Patent, is—

1. A fire-extinguisher-fluid holder provided with a top or cover proper, and a supplemental piece on its under side having a point or edge turned up against the top proper to admit of being pulled or jerked through the same, substantially as described.

2. A fire-extinguisher-fluid holder provided with a top proper, a supplemental piece on its under side having a point or edge turned up against the top proper to admit of being pulled or jerked through the same, and a staple passed down through the top proper and the supplemental piece, and fastened under or to such supplemental piece, substantially as described, and for the purpose set forth.

ERASTUS C. NELSON.
